UNITED STATES PATENT OFFICE.

HERBERT J. BRAGDON, OF CHICAGO, ILLINOIS, ASSIGNOR TO CHICAGO STOPPER CO., OF CHICAGO, ILLINOIS, A CORPORATION OF ILLINOIS.

STOPPER.

Application filed April 23, 1923. Serial No. 633,845.

My invention relates to a new seal or closure designed more particularly as a bottle closure but adapted for like use in the sealing of any suitably formed orifice, and 5 includes both the closure or seal and the method of applying the same. There have heretofore been in quite common use a variety of stoppers consisting of a disk of paper which when inserted in the bottle neck 10 bends upon a circular line or in an annular zone parallel to the periphery of the disk. In some of these previously used closures the bottle neck is provided with an annular groove, the neck of the bottle immediately 15 above the groove having a diameter less than the diameter of the disk and the bending of the disk permitting it to be forced past the relatively constricted part of the bottle neck after which its resiliency causes 20 it to return toward its initial flat form and become seated in the groove. In others of the previously used stoppers of this general type the disk is initially of considerably greater diameter than the bottle neck and 25 by pressure upon the central part of the disk it is forced into the bottle neck and given an annular bend which causes it to assume the form of a cup, the outer surface of the side wall of which lies against the interior 30 of the bottle neck in the completed closure. Closures of this type are not capable of resisting any considerable pressure and they are designed principally as stoppers for milk bottles, the only requirement being to exclude dirt during the brief interval between 35 the bottling and use of the milk. In closures of these types the only change or deformation imposed upon the disk in the act of forming the seal is the annular bending necessary to spring the disk into the groove in 40 the bottle neck or to cause it to assume the form of a cup with its side wall lying against the inside of the bottle neck. In these previously used stoppers consisting of 45 a disk of paper or similar material no attempt is made to seat the unbent disk in the bottle neck under direct pressure between its opposite edges and that result is not attained.

50 It is the purpose of my invention to insert a disk of paper or other yieldable material in a bottle neck in such manner as to form a liquid and gas tight seal which may be so applied as to be capable of resisting high pressure for an indefinite period of time as

distinguished from merely providing a cover for the temporary exclusion of foreign matter as in the case of milk bottle closures. I accomplish this purpose by forcing the disk into the inwardly converging bottle neck 60 under conditions which cause the disk to retain its flat and unbent form, the radially inward pressure of the converging walls upon the periphery of the disk having the effect of upsetting or swaging inwardly the 65 peripheral part of the disk and thereby imparting to it a thickened border section. When so inserted in a bottle neck the disk exerts great pressure outwardly against the 70 interior surface of the bottle neck, and as this pressure acts in the plane of the disk, which lies normal to the axis of the bottle neck, the only limit to the pressure that may be set up between the edge of the disk and the interior of the bottle neck is the 75 resistance of the material of the disk to compression and the strength of the bottle. The high degree of pressure which may be so obtained between the edge of the disk and the interior of the bottle neck establishes a 80 degree of friction between the disk and bottle neck that is capable of holding the disk in place against any internal pressure that can be withstood by the bottle. The inward radial pressure upon the edge of the disk necessary to secure this result is of so high a degree as to displace the material of the disk and compress it beyond its initial condition, and a material part of my invention 85 consists in the means which I have originated for causing this displacement to take the form of a flow or swaging of the peripheral border of the disk radially inward as distinguished from bending the disk along an annular line. 90

95 In the drawings forming part of this application I have illustrated means which I have employed for applying the seal and several different stages in the process of sealing a bottle.

100 Figure 1 is a longitudinal sectional view of a bottle neck with the sealing disk and tool or plunger used for applying the same shown in three successive positions.

105 Figure 2 is a plan view of the parts shown in Figure 1.

110 Figure 3 is a view in elevation and plan of a tool or plunger which I have used in applying the seal, the end part only of this tool being shown in Figure 1.

Figure 4 is a longitudinal sectional view of a bottle neck with a disk loosely resting therein, the plunger element being shown assembled with the disk and designed to remain in the bottle as part of the closure.

Figure 5 shows the parts illustrated in Figure 4 after being forced to sealing position.

Figures 6 and 7 are similar respectively to Figures 4 and 5 but show in addition an inclosing envelope and a wafer over the top of the stopper.

Figure 8 is a plan view of the plunger element forming part of the structure shown in Figures 4 to 7.

Figure 9 shows the stopper in an intermediate position while being removed from the bottle.

Figures 10 and 11 are detail views of the edge of the disk before and after insertion in a bottle neck.

Figure 12 is a view of the upper surface of a disk after insertion in a bottle to sealing position.

Figure 13 shows a stopper of the form illustrated in Figure 1 but with an envelope added, this stopper to be applied by the tool shown in Figure 3.

My improved sealing means in its entirety includes the use of a flat disk and a tool or plunger formed to apply pressure to the disk adjacent its periphery. The plunger may take the form of a tool, either hand operated or forming part of a machine, or the plunger may form part of the stopper or seal, both plunger and disk remaining in the sealed bottle. My invention also includes means for removing the stopper from a sealed bottle. For the purpose of clearness of explanation I will first describe my invention without reference to the means for removing the seal from sealing position.

In Figure 1 a bottle neck of ordinary form with an inwardly converging wall is shown. The convergence of the wall of the bottle neck is exaggerated in this and other views to more clearly show the action which takes place. The sealing disk 2 and applying tool or plunger 3 are shown in three successive positions exhibiting different stages in the formation of the seal. The applying tool, shown separately in Figure 3, is there illustrated as a hand tool. In a bottling machine the tool would, of course, form part of the machine and be mechanically actuated. The manner in which the tool cooperates with the disk, however, and its operation in forming the seal are the same whether it takes the form of a hand-operated instrument or forms part of a power-operated machine and hence the hand operated tool herein shown and described fully exhibits the principle of my invention. The tool as illustrated comprises a hollow cylindrical member 4 which may conveniently

consist of a section of metal tubing. The end of the tubular tool is inclined or beveled as shown at 5, the bevel inclining back toward the body of the tube from the edge of the inner cylindrical surface at an obtuse angle to the outer cylindrical surface, thereby producing a circular acute-angled edge at the inner cylindrical surface at 6 which will first contact with any plane surface to which the tool is applied, as appears in the first, or upper, position of the disk shown in Figure 1. The tube constituting the tool is also slotted longitudinally from the end as shown at 8. At 7 I have shown a handle or base mounted upon the tubular part of the tool. The projecting shoulder 25 at the inner end of base 7 will extend over the edge of the bottle neck and act as a stop to limit the inward movement of the plunger in the bottle neck.

In its uppermost position as shown in Figure 1, the disk 2 rests loosely in the upper part of the bottle neck, no pressure yet having been applied to it, and the tool 3 is shown as just establishing contact with the disk. As indicated, the first contact between the tool and disk is along the circular edge 6 at the inside of the cylindrical wall of the tool. An annular open space 9 of triangular cross section is thus left between the end of the tool and the peripheral portion of the upper surface of the disk at the beginning of the pressure of the tool upon the disk. By means of downward pressure upon the tool the disk 2 is forced to the lowermost position shown in Figure 1, and during this operation the disk is reduced in diameter by the convergence of the bottle neck and assumes the cross sectional form shown in its lowermost position. In this final sealing position the disk retains its perfectly flat form, the only deformation of the disk being the displacement of material which causes the formation of the upwardly projecting annulus or flange.

My investigation of the action which takes place during the application of pressure to the disk has developed the fact that the deformation of the disk results from the peripheral portion of the disk being upset or swaged inwardly and that the disk is not simply bent upwardly along a circular line or bent in any degree at any point. Evidence of this fact appears when before application to a bottle the edge of a disk is colored differently from the upper and lower surfaces and the location of this colored band is observed after the disk has been forced to the sealing position. In Figure 10 I have indicated by the bracket 11 the colored edge of the disk, and Figure 11 shows the same disk after being forced to the lowermost position shown in Figure 1. As indicated in Figure 11, the colored edge band 11 still lies upon the edge of the disk having been dis-

placed upwardly during the operation of thickened border section inclines outwardly to the edge of the disk.

In the middle position of the disk shown in Figure 1 the material of the disk has been displaced to an extent sufficient to fill the 70 annular space 9 shown in the first or uppermost position, and during the progress of this displacement the line of pressure between the tool and disk has widened from the sharp edge 6 to the entire area between 75 the edge 6 and the periphery of the disk.

The longitudinal slots 8 in the tool permit it to accommodate itself to the converging diameter of the bottle neck. The normal diameter of the tool is as great as that of the 80 larger part of the bottle neck and as the tool moves inward the prongs 16 between the slots bend toward the center thus diminishing the diameter of that part of the tube and by virtue of the resiliency of the 85 metal at all times preserving intimate contact between the lower end of the tube and the wall of the bottle neck. With this annular tool no pressure is applied directly to the central part of the disk and none is necessary as the central part of the disk inside of the edge 6 preserves its perfectly flat form under the procedure above described, and making the tool in the form of a hollow longitudinal, slotted cylinder affords convenient means as above described for enabling the end of the tool to adapt itself to the varying diameter of the bottle neck. If the 90 tool or plunger instead of taking the form of an annulus were constructed with a closed end normal to its axis inside of the angular edge 6 the pressure between the tool and disk would still be exerted principally if not in practical effect wholly along the edge 95 6 and the bevel outside of said edge. It is, of course, essential that the edge 6 be not so far removed from the periphery of the disk as to permit the disk to bend. The 100 most advantageous distance of the edge 6 from the periphery of the disk will depend principally upon the thickness and diameter 105 of the disk and the material of which it is made.

I have found that with the disks I have used the best results are obtained by forming the bevel 5 at the end of the tool at an angle of about ten degrees to a plane normal to the axis of the tube. Material departure from the ideal angle brings about inferior 110 results, the seals so obtained not being capable of resisting so high a pressure and the swaging not being effected so uniformly around the periphery of the disk. When the end of the plunger instead of being inclined as shown at 5 in Figure 3 is normal, or nearly so, to the axis of the plunger, the 115 deformation and compression of the disk is irregular and the effect upon different disks of identical material and form is not uni- 120 125 130

placed upwardly during the operation of thickened border section inclines outwardly to the edge of the disk.

In the middle position of the disk shown in Figure 1 the material of the disk has been displaced to an extent sufficient to fill the 70 annular space 9 shown in the first or uppermost position, and during the progress of this displacement the line of pressure between the tool and disk has widened from the sharp edge 6 to the entire area between 75 the edge 6 and the periphery of the disk.

The longitudinal slots 8 in the tool permit it to accommodate itself to the converging diameter of the bottle neck. The normal diameter of the tool is as great as that of the 80 larger part of the bottle neck and as the tool moves inward the prongs 16 between the slots bend toward the center thus diminishing the diameter of that part of the tube and by virtue of the resiliency of the 85 metal at all times preserving intimate contact between the lower end of the tube and the wall of the bottle neck. With this annular tool no pressure is applied directly to the central part of the disk and none is necessary as the central part of the disk inside of the edge 6 preserves its perfectly flat form under the procedure above described, and making the tool in the form of a hollow longitudinal, slotted cylinder affords convenient means as above described for enabling the end of the tool to adapt itself to the varying diameter of the bottle neck. If the 90 tool or plunger instead of taking the form of an annulus were constructed with a closed end normal to its axis inside of the angular edge 6 the pressure between the tool and disk would still be exerted principally if not in practical effect wholly along the edge 95 6 and the bevel outside of said edge. It is, of course, essential that the edge 6 be not so far removed from the periphery of the disk as to permit the disk to bend. The 100 most advantageous distance of the edge 6 from the periphery of the disk will depend principally upon the thickness and diameter 105 of the disk and the material of which it is made.

I have found that with the disks I have used the best results are obtained by forming the bevel 5 at the end of the tool at an angle of about ten degrees to a plane normal to the axis of the tube. Material departure from the ideal angle brings about inferior 110 results, the seals so obtained not being capable of resisting so high a pressure and the swaging not being effected so uniformly around the periphery of the disk. When the end of the plunger instead of being inclined as shown at 5 in Figure 3 is normal, or nearly so, to the axis of the plunger, the 115 deformation and compression of the disk is irregular and the effect upon different disks of identical material and form is not uni- 120 125 130

form though a closure sufficient for some purposes may be so obtained. I have used disks made of a variety of paper and fibrous composition, and have obtained good results 6 with the material known as press board.

In Figures 4 and 5 I have shown a modified form of the closure. In this modification the bevel is formed upon an element which forms part of the closure. The closure 10 comprises a disk 13, similar to the disk 2 above described, but in this form a ring or annulus 14 is assembled with the disk and forms part of the stopper. This ring 14 is beveled on its lower edge at 17, the 15 bevel being similar to that formed upon the tool illustrated in Figures 1 to 3 above described. The ring 14 is preferably, though not for all purposes necessarily, made of a material more rigid than the disk, and it is 20 preferably provided with a diagonal joint 18 (Figure 8) to permit contraction of the diameter of the ring as it moves inward in the converging bottle neck. The ring may 25 conveniently be made from a straight strip 30 of material of proper cross section cut to proper length and bent to circular form. The ring may be attached to the disk by an adhesive applied along the inner edge of the ring or may be otherwise assembled with 35 the disk in such manner as to permit it to break loose therefrom to accommodate the relative movement of the ring and disk when being forced into position in a bottle neck. It is not necessary, however, except for 40 convenience that the ring and disk be secured together. The stopper may be forced from the position shown in Figure 4 to that shown in Figure 5 by means of a mallet, the 45 parts being so proportioned that when the upper edge of the ring is hammered down about flush with the upper edge of the bottle neck the disk will have been moved to sealing position. During this inward movement the beveled ring acts upon the disk 50 precisely as above described in connection with the action of the tool shown in Figures 1 to 3, and the completed closure consists of the disk 13 and the ring 14 as shown in their lowermost position in Figure 5.

The disk 13' and ring 14' shown in Figures 6 and 7 are similar to the corresponding parts shown in Figures 4 and 5, but the structure shown in Figures 6 and 7 embodies in addition an envelope 20, preferably of tough paper, covered on the upper side or on both sides with metal foil if desired. The envelope is preferably made of sufficient size to be pressed over the edge and a short distance down upon the outside of 60 the bottle neck after the stopper is forced to sealing position as indicated at 20' in Figure 7, and a wafer 21 secured around its edge to the other parts of the stopper 65 may be used to give the stopper a flush top and to bear any desired printed matter. The

space inside of the annulus 14' and between the disk and wafer may, if desired, be filled with some yielding material such as a loosely wound roll of soft paper in order to better support the wafer. The different elements of the stopper or part of them may be assembled and secured together prior to application to a bottle or they may be assembled as used. In Figure 13 I have shown a disk 2' corresponding to the disk 2 shown 70 in Figure 1 but with an envelope 20^a assembled therewith. The stopper shown in Figure 13 may be applied by means of the tool shown in Figure 3, or by means of the ring 14' shown in Figures 6 and 7. The envelope 75 with either form of stopper performs an important function in providing means for easy removal of the stopper from the bottle. In sealing position the disk is seated normal to the axis of the bottle neck and under high 80 pressure against the wall thereof. So long as the disk remains in this position with the pressure from opposite sides acting in direct line through the body of the disk it will resist great pressure within the bottle 85 and will oppose great resistance to an effort to pull it out for the purpose of opening the bottle. It is comparatively easy, however, to dislodge the disk from sealing position 90 by applying force to it at one side only, thereby tilting the disk from its position normal to the axis of the bottle neck, in which position the opposing pressures are no longer in line and are relieved by the inclined position of the disk. Removal of the 95 stopper is therefore easily accomplished by grasping the edge of the envelope at one side as indicated at 22 in Figure 9, in which view a stopper of the type shown in Figure 1 is illustrated, i. e. a stopper applied 100 by means of the tool shown in Figure 3. By means of an upward pull at 22 the disk is easily tilted to the inclined position indicated, whereupon it is easily removed. The stopper shown in Figure 7 may be removed by the same procedure, the ring or 105 annulus 14' yielding to permit the tilting movement. An upward pull upon opposite edges of the envelope simultaneously has no 110 tendency to tilt the disk and the resistance is so great as to render it impractical to open a tightly sealed bottle in that way.

In Figure 12 I have shown the appearance of a disk after having been forced to sealing position by the tool shown in Figure 3. The movement of the material inward radially from the edge of the disk causes an 115 appearance of crimping, most noticeable, when the tool 3 is used, at the six points designated 24 where the material has been displaced upwardly into the slots 8 in the tool, but also noticeable as fine lines 23 between the slots.

The stopper herein described may be applied to produce a liquid and gas tight seal 120

capable of resisting higher pressures than those to which bottles are subjected in practice. The stopper, moreover, is equally well adapted for use with substances not under pressure as the pressure resisting capacity of the stopper is obtained without the introduction of any element of cost or mechanical structure not equally applicable and efficient in a stopper designed for general use. For some purposes, such as the bottling of carbonated water, it is not required that stoppers be so constructed that they may be applied, after the bottle has been opened, for the purpose of re-sealing it, but for other purposes it is generally necessary that a stopper be capable of repeated use with efficiency for the purpose of re-sealing the bottle as the contents are gradually used. My improved stopper is capable of such repeated use and forms an efficient re-seal, it being necessary simply to press downward upon the disk shown in Figure 9 or upon the upper edge of the annulus shown in Figure 7 to restore the stopper to sealing position.

What I claim is:

1. A closure for a substantially circular orifice having an inwardly converging wall, said closure comprising a disk having a substantially flat inner surface, the outer surface of said disk having a flat central portion surrounded by an outwardly projecting

annular flange, said outwardly projecting flange consisting of the part of said disk which is permanently swaged by the pressure resulting from its insertion in said orifice. 35

2. A closure for a substantially circular orifice having an inwardly converging wall comprising a disk substantially perpendicular to the axis of said orifice and having a peripheral zone thicker than the central part of said disk and separated therefrom by an upwardly projecting shoulder, the pressure between the edge of said disk and the wall 45 of said orifice being sufficient to swage radially the material of a disk initially having parallel flat faces.

3. A closure for a substantially circular orifice comprising a disk extending across 50 said orifice, the inner side and the central part of the outer side of said disk being parallel plane surfaces substantially normal to the axis of said orifice, said disk having an annular border section of greater thickness than its central part and lying between the edge of the disk and an outwardly projecting annular shoulder on the outer side thereof, the outer surface of said thickened border section inclining outwardly from said 55 shoulder to the edge of said disk.

In witness whereof, I hereunto subscribe my name this 20th day of April, A. D., 1923.

HERBERT J. BRAGDON.
